UNITED STATES PATENT OFFICE

OSCAR C. SCHROEDER, OF CHICAGO, ILLINOIS, ASSIGNOR TO GENERAL ELECTRIC COMPANY, A CORPORATION OF NEW YORK

BRUSH HOLDER

Application filed February 9, 1928. Serial No. 253,191.

My invention relates to brush holders for electrical machines and has for its object the provision of a brush holder which will prevent chattering of the brushes. I accomplish this by the use of a simplified brush holder including a brush guide in which the brush spring extends along the brush and is supported between the brush and the brush guide so that the force of the spring urges the brush against the current collecting device and against the trailing side of the brush guide with respect to the direction of rotation of the current collecting device of the machine in which it is used. Urging the brush against the trailing side of the brush guide in this manner substantially prevents chattering of the brush because vertical movement which would cause chattering is resisted by the friction of the brush in the brush guide; and lateral movement which would cause chattering is resisted by the frictional force between the brush and the current collecting device and the action of the brush spring which produces a lateral force acting in the same direction. In addition to preventing chattering of the brushes this construction has the further advantage of simplifying the brush holder and enabling one to use a tension spring therein which will maintain the desired brush pressure on the current collecting device without adjustment as the brush is worn away.

Further objects and advantages of my improved brush holder will become apparent as the following description proceeds, and the features of novelty which characterize the same will be pointed out with particularity in the claims annexed to and forming a part of this specification.

In the drawing, Fig. 1 is a longitudinal section of my improved brush holder, Fig. 2 is a transverse section on the line 2—2 of Fig. 1, and Fig. 3 is a diagrammatic view indicating the external forces acting on the brush.

Referring to the drawing, a current collecting device 10 of an electrical machine rotates in the direction indicated by the arrow 11 and a brush 12 is supported in contact therewith by my improved brush holder.

This brush holder comprises a tubular, metal brush guide 13 having a longitudinal opening 13^a extending therethrough slidably fitting the brush 12. In order to minimize chattering of the brush a suitable spring is arranged along the side of the brush and supported in such manner as to exert a force which urges the brush toward the current collecting device and toward the trailing side of the brush guide with respect to the direction of rotation of the machine. In the construction illustrated by way of example, it is preferred to do this by forming a recess which in this instance is shown as a groove 13^b in the wall of the leading side of the brush guide extending longitudinally of the brush and arranging a tension spring 14 in the recess which is connected to the brush guide by a cross pin 14^a and to the brush by a connector 15. The connector extends into an opening 12^a in the top of the brush and to one side of the same into the groove 13^b where it engages a loop 15^a formed on the end of the spring.

In this construction it will be noted that the direction of the external forces acting on the brush are, as shown in Fig. 3, the force F of the spring 14, the resisting force R exerted by the current collecting device 10 on the brush 12, and the forces r' and r'' exerted by the brush guide on the brush 12. The brush is maintained in equilibrium under the action of the spring 14 as the forces F and R produce a moment tending to turn the brush about an intermediate transverse axis which is resisted by an equal and opposite moment produced by the forces r' and r'' which represent the forces exerted by the brush holder 13 on the brush. It will thus be seen that the spring 14 increases the pressure and friction between the brush and the trailing side of the brush guide so that vertical movement of the brush tending to cause chattering is resisted but not enough to prevent the brush sliding in the brush guide under the action of the spring 14 and following any irregularities in the surface of the current collecting device. Moreover, during operation of the machine, the frictional force between the current collecting device and the brush acts

to increase the pressure between the brush and the trailing side of the brush guide so that the brush is prevented from vibrating laterally which would tend to cause chattering. Arranging the spring 14 along the side 5 of the brush in this manner permits the use of a long spring which can be selected to exert the desired pressure on the brush from the time a new brush is inserted in the holder until most of it is worn away.

10 The brush guide may be supported by any suitable means, but in the construction illustrated it is pressed into a cap 16 of insulating material which is moulded in a metal brush holder support 17 with pins 16¹ projecting therefrom through openings 17¹ formed in the wall of the support. The brush may be connected in the circuit of the machine in any suitable manner such as a clamp 15 on the brush guide or the usual pig-tail connection.

15 In the view of the foregoing, it will be clear that I have produced a simplified brush holder which can be easily constructed and which will substantially prevent chattering.

20 What I claim as new and desire to secure by Letters Patent of the United States is:

1. In combination with a current collecting device having a brush bearing thereon, 25 a brush holder comprising a tubular guide for said brush, said brush guide having a groove in the side wall thereof opening toward said brush and formed to receive a spring, a tension spring arranged in said 30 groove and extending along the leading side of the brush, means for connecting one end of said spring to the top of the brush and the other end thereof to said guide so as to urge said brush against said current collecting device and the trailing side of said guide 35 so as to prevent chattering of the brush, and a support secured to said tubular guide.

2. A brush holder comprising a tubular brush guide member having a groove in the 40 side wall thereof, a spring arranged in said groove having one end connected to the upper portion of the brush and the other end connected to the lower portion of said guide, an insulating cap on said guide member, and 45 a support fitted on said cap.

3. A brush holder comprising a tubular brush guide member having a groove in the 50 side wall thereof, a spring arranged in said groove, a wire extending into a longitudinal 55 opening in the brush and engaging the upper end of said spring for connecting the same to the brush, and a pin carried by said guide member connecting the lower end of said spring thereto.

60 4. In combination with a current collecting device having a brush bearing thereon, a brush holder including a tubular brush guide member having an axial opening serving as a guideway for the brush and a groove of 65 smaller width throughout than said guide-

way and opening toward the same, a spring arranged in said groove and extending along the brush, means for supporting said spring between the brush holder and the brush for urging the latter against said current collecting device and the trailing side of said guide so as to prevent chattering of the brush, and means for supporting said tubular brush guide member in operative relation to said current collecting device.

70 In witness whereof, I have hereunto set my hand this 3d day of February, 1928.

OSCAR C. SCHROEDER.
